BY
Adam E. Fisher
ATTORNEY

UNITED STATES PATENT OFFICE.

LEANDER P. SHAW, OF BRADFORD, PENNSYLVANIA.

LOCK JOINT FOR RODS.

1,403,201.

Specification of Letters Patent. Patented Jan. 10, 1922.

Application filed March 18, 1921. Serial No. 453,231.

To all whom it may concern:

Be it known that I, LEANDER P. SHAW, a citizen of the United States, residing in the city of Bradford and State of Pennsylvania, have invented new and useful Improvements in Lock Joints for Rods, of which the following is a specification, reference being had to the accompanying drawings.

This invention pertains to lock joints for rods, and is especially designed for use upon the sucker rods of pumps and oil wells.

The object is to provide a simple and efficient lock joint of this kind which may be much more readily and quickly adjusted for interlocking the abutting ends of such rods than the ordinary devices employed.

In the drawings:

Figure 1 is a side elevation of the stub end of the sucker rod;

20 Figure 2 is an end view of the same;

Figure 3 is a side elevation of the fork end of the other rod to be joined, showing the key fork partially advanced;

Figure 4 is an end view of the same;

25 Figure 5 is a detail of the key fork removed from the guide slots formed in the end of the rod.

Figure 6 is an assembly view.

Figure 7 is a detail of the lock fork.

30 The invention consists in chambering out the stub end 1 of one sucker rod 2, at each side so as to leave the main lead grooves 3 extending to the end of the rod, the lateral, oppositely directed lock recesses 4, which 35 form the oppositely directed lock shoulders 5, and finally the shallow surface recesses 6 extended laterally from the main grooves 3 and also reaching to the end of the rod.

40 The end 7 of the other rod 8 which is to be joined to the rod 2, is formed to embody an integral lock fork 9, the tines 10 whereof have inwardly turned lock lugs 11, adapted to slide longitudinally within the main lead grooves 3 of the end 1 and then, turning laterally, to engage the lock shoulders 5, thus preventing longitudinal stress from separating the rods. At the same time the tines 10 turn laterally into the surface recesses 6, thus presenting a uniform and even outer 50 surface along the two rods. Guide slots 12 are chambered out, one at one side of each

of the tines 10, and oppositely positioned to each other. These guide slots 12 extend clear out to the end of the rod 8 at their outer ends, while at their inner ends a connecting mortise or recess 13 is cut clear through, thus joining the guide slots 12 at their said inner ends.

Within these guide slots 12 is slidably mounted the key fork 14, the lock prongs 15 whereof are connected through the mortise 13, and are adapted to slide outwardly alongside the tines 10 and into the grooves 3, thus locking the lugs 11 into engagement with the shoulders 5. To unlock or disconnect the two rods, the key fork 14 is drawn back from the grooves 3, after which the lugs 11 may be twisted or turned laterally out of the recesses 4 and from engagement with the shoulders 5, and the rods may be pulled apart.

70 While I have herein described a certain specific method of constructing and assembling the elements of my invention, it is understood that the same may be varied in minor details, not departing from the spirit 75 of my invention as defined in the appended claims.

What I claim to be new and patentable is:

1. A lock joint for rods, consisting in chambering out one end of one rod to 80 form oppositely positioned longitudinal lead grooves, laterally connected and extended shallow recesses, and deeper lock recesses and resulting shoulders at the inner ends of the shallow recesses; an integral lock fork 85 with inwardly turned lock lugs formed at one end of the other rod, said lugs being adapted to travel the grooves aforesaid and to laterally engage the said lock recesses of the first mentioned rod; rearwardly connected guide slots formed one at one side of each of the tines of the said fork; and a key fork slidably mounted in said guide slots, the prongs thereof being adapted to travel the grooves in the end of the first 90 mentioned rod, for locking the lock lugs against the lock shoulders.

2. A lock joint for rods, comprising longitudinal lead grooves and lateral lock shoulders formed in one end of one rod; a lock fork with lock lugs on the tines thereof formed on one end of the other rod and

adapted to engage said lead grooves and of the lock fork for holding said lock lugs
lock shoulders; guide slots formed at the in engagement with the lock shoulders.
sides of the tines of said fork, same being
connected by a mortise at their inner ends;
5 and a key fork slidingly mounted in said
guide slots, its prongs being adapted to
travel said lead grooves alongside the tines

LEANDER P. SHAW.
